CLAIM

The ornamental design for a flexible printed circuit, as shown and described.

DESCRIPTION

FIG. 1 is a front view of a flexible printed circuit showing our new design;

FIG. 2 is a rear view thereof;

FIG. 3 is a top view thereof;

FIG. 4 is a bottom view thereof;

FIG. 5 is a right view thereof;

FIG. 6 is a left view thereof; and,

FIG. 7 is an enlarged portion view delimited by the lines labelled 7 in FIG. 1.

The even broken lines in the drawings depict unclaimed subject matter only and form no part of the claimed design. The dashed-dot lines in the drawings depict a boundary between the claimed design and the unclaimed subject matter and form no part of the claimed design.
